CRUSHER AND PRESSURE-EXERTING
MACHINERY

Samuel William Traylor, Jr., Allentown, Pa., assignor to Traylor Engineering & Manufacturing Company, Allentown, Pa., a corporation of Delaware

Application September 30, 1931, Serial No. 566,051

21 Claims. (Cl. 83—16)

The invention relates to gyratory crushers, and to the regulation of working pressure and stress in crushing or pressure-exerting machinery. The invention affords a simple and compact crusher that is easy and economical to build, and can be made very rugged and powerful. The invention affords a new way of adjusting such machinery according to the degree of fineness or coarseness of product desired, and of controlling the working pressure and preventing excessive pressures and stresses.

In the drawings, Fig. I is a vertical section through a gyratory crusher and associated apparatus, embodying my invention.

15 Fig. II is a vertical section of a modification.

Fig. III is a fragmentary vertical sectional view of the lower portion of the device shown in Fig. II, with certain parts in full that are there shown in section.

20 Fig. IV is a similar view illustrating another modification.

Fig. V is a vertical mid-section illustrating a different type of crusher from that shown in Fig. I.

25 The crusher shown in Fig. I comprises a crushing hopper or shell 10 located in the upper portion of the hollow frame or casing 11, and a gyratory member 12 provided with a crushing head 13 gyrating in the shell 10, and cooperating therewith to crush material in the varying interval between them. The gyratory member 12 is actuated by a rotary eccentric 14, which is engaged or journalled around the shaft portion 15 of the member 12 below its head 13, and is externally journalled in a hub-like structure 16.

30 In the present instance, the shaft 15 is shown integral with the head 13. The hub 16 is connected to the frame or casing 11 by spoke-like webs 17 and a hollow countershaft bearing boss 18,—all preferably cast integral with the frame

35 11. The gyratory member 12—or a downward extension 20 of its shaft portion 15—has its neutral, non-gyrating point of no throw 21 in the lower portion of the casing 11, where its lower end engages and rests on a bearing disc 22 seated in a depression in the upper end of a supporting boss 23. The boss 23 forms part of a hollow drum-like bottom structure 24 that is suitably secured to the lower end of the hub 16. Provision may be made to prevent the shaft extension 20 from turning, as by anti-turning engagement of an angular (square) form of projection 21a on the extension 20 in a correspondingly formed socket in disc 22 and boss 23. If desired, radial oil grooves may be provided at

21, at suitable intervals in the lower end surface of the extension member 20 and in the coacting bearing surface at 22, to permit oil to work in between them more readily.

The eccentric 14 has an external step bearing 5 shoulder 25 that rests on a step bearing formed by one or more bronze rings 26 seated in a rabbeted seat on an internal flange 26a at the upper end of the bottom 24. On the eccentric 14, just above the step bearing 25, is a bevel driving gear 27 that meshes with a bevel pinion 28 on the inner end of a countershaft 29 mounted in a bearing bracket structure 30, which is mounted and secured in the bore of the boss 18. The countershaft 29 may be driven from any 10 suitable source of power, to rotate the eccentric 14.

As shown in Fig. I, the shaft 15 of the gyratory member 12 is hollow and the extension 20 telescopes therein with a sliding fit, like a plunger, 20 so that parts 12 and 20 together form a gyratory member that is variable in length, though substantially inflexible laterally as if they were one solid shaft,—like the gyratory member 12 of Figs. II-V. Hydraulic packing 39 is provided at 25 the upper end of the member 20 to make a fluid-tight joint. To facilitate removal of the gyratory parts from the crusher, a lost-motion connection of the extension 20 to the member 12 may be provided, consisting of a rod 32 30 screwed into the upper end of the member 20 and extending up through a bore in the member 12 to an enlarged and diametrically grooved head 33 loosely accommodated in a recess 34 in the head 13. A removable screw plug 35 and cap 36 35 afford access to the head 33 when necessary. To shift the parts 20 and 15, 13 in the axial direction relative to one another, fluid can be admitted to the cylinder bore 40 of the member 12, above the plunger 20 (or vented therefrom), through 40 a duct 41 extending down through the center of the plunger and its non-gyrating engaging portion 21a, with a flexible tube connection 42 from its lower end out through the bottom structure 24 to a pipe connection 44. Thus the effective length of the gyratory member 12 can be varied, and the head 13 can be raised and lowered relative to the shell 10 to vary and regulate the size of the crushed product. In other words, the cylinder bore 40 and its plunger 20 constitute 45 a hydraulic motor for varying the effective length of the gyratory member 12, and raising and lowering the crushing head 13. Against normal crushing stresses, the head 13 can be firmly sustained by the fluid, while by yielding of this 50 55

fluid support under abnormal working stresses, the shaft and head can be allowed to recede downward, to relieve such stresses and protect the machine against damage from tramp iron getting in the crushing shell 10, or the like.

The fluid supply and discharge pipe 44 is shown connected to the delivery side of a plunger or other pump 45, provided with intake and discharge check valves 46, 47, and drawing from the bottom of a supply vessel 48. The pump 45 may be run continuously whenever the crusher is in operation, or it may be run intermittently, when and as required. As here shown, the vessel 48 includes two compartments or receivers 50, 51, the former open but provided with a removable cover 52, and the latter closed. From the bottom of the open (upper) receiver 50, there is a delivery connection to the closed (lower) receiver 51, controlled by a hand valve 54. The receiver 51 is provided with a drain connection and valve 55. From the delivery side of the pump 45 and its discharge valve 47, there are bye-pass connections to the receivers 50, 51, through a pipe 56 with branches 57, 58. In the connection 57 of the receiver 50, there is a stop hand valve 59; while in the connection 58 to the receiver 51, there is an automatic pressure-controlled relief valve 60. A pressure gauge 61 may be connected to the connection 56, if desired, to show the pressure in the high-pressure side of the system. The receiver 51 may be provided with a hand-valve controlled air vent 62 from its highest point.

As here shown, the lower end of the crushing head 13 has a cylindrical surfaced internal shoulder or cavity formed by a depending skirt or flange 65. The corresponding portion of the hub 16 has an external annular groove 66, in which is mounted a sealing ring 68 whose cylindrical periphery engages with the cylindrical inner surface of the head 13 at 65. The coaxing surfaces of the ring 67 and of the sides of its groove 66 are preferably spherical, and concentric with the neutral point of the member 12 at 21. The ring 67 permits free gyratory movement of the head 13, and does not interfere with its vertical adjustment, but nevertheless forms a tight seal between the head 13 and the hub 16 against ingress of dust or dirt and against egress of oil or lubricant. In the present instance, similar sealing is provided between the exterior surface of the gyratory shaft 15 and the upper end of the hub 16, by means of a sealing ring 68 mounted in an internal annular groove 69 between shoulders at the upper end of a (separate) bearing liner or bushing 70 in the hub 16. The inner cylindrical surface of the ring 68 engages the cylindrical outer surface of the shaft 15. The coaxing surfaces of ring 68 and of the sides of its groove 69 are preferably spherical and concentric with the neutral point 21.

While either of the seals 67 and 68 might be omitted, their combination presents important advantages. Without the seal 68, oil working or thrown upward, above the eccentric 14 and hub 16, would run down on the seal 67 and work its way down past the latter, caking dust below it into a ridge or shoulder that would have to be broken away whenever the head 13 was raised after prolonged operation at one setting. Without the seal 67, dust would have access to the shaft 15 above the seal 68, and oil creeping up past the seal 68 would cake such dust into a ridge or shoulder above the seal 68 that would have to be broken away on lowering the head 13. 75 Failure of these caked dust ridges to break away

clean would tend to injure and impair the effectiveness of the seal rings 67, 68.

From the foregoing description, it will be seen that the operating mechanism (eccentric 14, gears 27, 28, neutral bearing and support at 21, 5 22, etc.) is all enclosed and sealed in the interior of the crusher, in the chamber afforded by the hub 16 and bottom structure 24. Thus all the working and wearing parts and surfaces are enclosed and included in the main lubricating 10 system of the crusher, and thoroughly lubricated. When the crusher is at rest, the oil supply in the enclosure forms a pool that extends up upon the teeth of the gear 27; when the crusher is in 15 operation, the oil level is lower, but still extends above the lower end of a helical groove 72 (of comparatively large pitch) in the external surface of the shaft 15. During the operation of the crusher, therefore, oil is lifted into the interior of the eccentric by the groove 72, and is raised 20 or wiped upward in the groove by the combined action of centrifugal force and of friction between the interior of the revolving eccentric and the exterior of the shaft 15,—which does not revolve,—thoroughly lubricating the interior of the 25 eccentric. Reaching the top of the eccentric 14, the oil descends in grooves 73 in the bearing surface of the bushing 70, thoroughly lubricating it. Some of this oil flows outward over the teeth of gear 21, lubricating its contact with pinion 28. 30 Oil also flows down and out through a port or passage 74 in sleeve 10 and hub 16 to a chamber 15 in the bearing bracket 30, whence it runs through ports 76 to the countershaft 29. This oil works its way inward and outward through the 35 countershaft bearings, and finally returns through ports 77, 78, 79 to the pool beneath the gear 27.

As shown, there is an annular baffle 80 depending from the flange 26a of the bottom drum 24, and extending down to a considerable depth 40 in the oil pool. In the pool, and preferably in the path of circulation produced by the baffle 80, cooling means may be provided, here shown as located inside the baffle 80, and as consisting of a double helical pipe coil 83, with supply and discharge connections 84, 85 down through the bottom of the drum 24, for the circulation of cooling water. As shown, the coil convolutions 83 are mounted in openings in suitably constructed ribs or radial baffles 86, located at such circumferential intervals as to support the coils properly. 50 Below the bearing 23 and the baffle 80 is a dead space, around the boss 24, for dirt to settle out of the oil flow.

The downward-flared crushing shell 10 may be 55 surfaced with a separate lining 90 (usually termed a "concave") removably mounted in the upper end of the frame or casing 11, which latter may be made in one piece. The concave 90 can also be made in one piece or without vertical division: as here shown, it consists of a single annular member, held in place by superjacent annular securing means 91. The concave 10 is flared 60 downward externally as well as internally: accordingly, the securing means 91 is shown of a corresponding wedge section, to fit in the cylindrically bored upper portion of the frame 11 around the concave 90, and hold the latter securely. The frame 11 and the wedge means 91 are shown with external flanges 92, 93, through 65 which extend securing bolts 94. The frame 11 is internally shouldered at 95, as a means of seating and sustaining the concave 90 in the frame. The circular wedge 91 has a sliding fit in the frame 11, and has its inner conical surface machined to 70 75

fit the concave 90, which may be a ground machine fit in said part 91, or may have a supporting filler of spelter, or any other means of making a joint. The frame 11 is taper bored at 95 in conformity to the conical edge of the concave 90. By pulling up the bolts 94 tightly, the wedge flange 93 is drawn to frame flange 92, the wedge 91 is clamped in the frame 11, and the concave 90 is forced home and held securely against movement due to the crushing stresses.

The wedge means 91 may, if desired, be split at several points, to facilitate its removal from the frame 11 when required. The rim 93 may be protected from wear by wearing plates 96. By operating the crusher after loosening the bolts 94, the wedge means 91 and the concave 90 will be loosened in the frame 11 so as to be easily lifted out.

In the operation of the crusher, the point of greatest motion of the gyratory member 12 is at the top, in the head 13, while the point of no-motion is at the bottom, at 21, and the eccentric and its external bearing in the hub 16 are intermediately located, close below the head. This not only allows the usual spider support above the head 13 to be eliminated, but also allows a heavier and stronger shaft 15 to be used, and an eccentric 14 of larger diameter, smaller throw, and greater power, and also of more ample bearing surface for a given axial length. This follows from the fact that the gyratory throw of the head 13 exceeds that of the eccentric 14, instead of being less, as in the ordinary crusher with fulcrum at the top and eccentric at the bottom. This naturally results from the location of the neutral "point of no throw" of the member 12 below the eccentric 14, at the neutral no-throw bearings 21, 22. The point 21 is made thus neutral by internally boring the eccentric 14 to an axis X which would intersect the axis X of the external surface of the eccentric at 21 i. e., an axis X suitably inclined relative to the axis X of the external surface of the eccentric.

With respect to vertical adjustment and automatic protection against excessive stresses due to the presence of "tramp" iron or the like in the crushing shell 10, it will be seen that while the gyratory member 12 has a fixed neutral point of no-throw engagement and support at 21, yet it can be varied in effective length to raise and lower the head,—either to adjust for fine and coarse crushing, or to protect the crusher from damage by excessive crushing stresses,—by the action of the variable hydraulic support or motor at 40, which is both adjustable and automatically yielding as hereinafter explained.

Supposing that the crusher and the pump 45 have been shut down, and the valves 59, 54, and 55 opened, the gyratory head 13 and shaft 15 will be resting on the central upper surface of the plunger 20, and the compartments 50, 51 will both be empty. When the crusher is to be used, the valves 59 and 55 are closed, the pump 45 is started (either by its own motor, or by the starting of the crusher, if the pump is driven therefrom), and a liquid, such as oil, is put into the compartment 50. The valve 54 being open, or presently opened, the oil will run down into the receiver 51, and (as fast as it reaches the receiver 51) drawn off by the pump 45 and forced into the cylinder 40, raising the crushing head 13 correspondingly. When the desired adjustment of the head 13 is thus reached (to give the desired size of product), the valve 54 is closed. The relief valve 60 being suitably adjusted, the oil will be

held confined, and the head 13 fixedly supported at the desired height under the normal working pressure. If it is desired to raise the head 13 higher, the valve 54 will be opened, and more oil will be pumped into the cylinder 40; if it is desired to lower the head, the valve 59 will be opened until the necessary amount of oil has been drawn off into the receiver 50. By keeping a definite amount of oil in the system, the crusher can always be reset to a desired maximum fineness of product by merely opening the valve 54 and leaving it open.

If tramp iron or other hard material in the shell 10 gives rise to excessive working thrust and pressure, the relief valve 60 will open and allow the head 13 to yield,—the oil thus vented from the cylinder 40 flowing back through the bye-pass 56, 58 to the receiver 51 and short-circulating through this by-pass as long as the working pressure and thrust in the machine remain unduly high. Whenever the abnormal condition is relieved, the oil is automatically repumped back into the cylinder 40, and the crusher thus restored to its intended working adjustment.

When all the oil has been forced into the pressure line by the pump 45, the latter will draw in air on the subsequent suction stroke; but this air will not be compressed sufficiently to enter the line on the succeeding working stroke,—the pump displacement and clearance being so chosen as to assure this.

Figs. II and III illustrate another simple way of adjusting a crusher of the general type shown in Fig. I. Here the telescopic shaft extension or plunger 20 of Fig. I is dispensed with, and the lower end 15a of the main gyratory shaft 15 (which is solid) rests directly on the bearing support disc 22, which is vertically adjustable, and may be engaged therein at 21a. The disc 22 rests on a plunger 23a which is mounted in a cylinder bore or guide 23b in the boss 23 of the bottom structure 24, and is supported by a screw 23c threaded through the bottom structure 24, like a set-screw. As shown, the disc 22 is engaged and guided in an enlargement of the bore 23b. By screwing the screw 23c up and down, the shaft 15 and the whole gyratory member can be vertically adjusted to vary and regulate the fineness or coarseness of the crushed product.

If desired, the plunger 23a may be equipped with hydraulic packing 23d and the cylinder 23b may have a pressure fluid connection 44 to a system such as shown in Fig. I. This allows the vertical adjustment to be made hydraulically, and also permits automatic yielding and recession of the head 13 as in Fig. I. Thus the screw 23c becomes no more than a clean-out plug, or a stop for limiting the coarsening adjustment by fluid. Any preferred means may, of course, be used to introduce and draw off fluid from the cylinder 23b.

Fig. IV illustrates an arrangement similar to Figs. II and III, but embodying a spring cushion support arrangement in lieu of the simple solid plunger of Figs. II and III. For this purpose, there are plunger members 23e, 23f with interposed helical compression-springs 23g, whose ends are seated in recesses 23h in the members 23e, 23f. The members 23e, 23f are interconnected by tension bolts 23i whose conical heads 23j are engaged and accommodated in conical counterbores 23k in the member 23e, and whose nuts 23l are accommodated in recesses 23m in the member 23f. The bolts 23i may preferably extend through the springs 23g. When the cushion device is put in

place, its springs 23g are pretensioned, by the bolts 23i, to sustain the normal crushing stresses without yielding; but if excessive stresses are encountered, the springs yield and afford relief 5 and protection.

If desired, hydraulic packing 23d may be provided on plunger member 23e, and a fluid connection 44, allowing the device to be adjusted by fluid as indicated in connection with Fig. II.

10 Fig. V illustrates fluid support and adjustment arrangements applied to a more ordinary type of crusher, whose shaft 15 extends above the head 13 at 15b and is there engaged in a spider 100a, so that the greatest motion of the gyratory member 12 is at the lower end, which is actuated by the eccentric 14a. The gyratory member 12 is not supported from the bottom, as in Fig. I, but from the top, i. e., the fluid cylinder and plunger are at the top of the gyratory shaft 15b, whose 15 lower end may be directly engaged and actuated to gyrate the gyratory member 12, without any plunger extension 20 or 20a. In this case, the split tapered nut 101a in the taper bore of the sleeve 102a is screwed directly on the upper end 20 of the shaft 15b, and the lower end of the sleeve 102a constitutes an annular plunger in an annular cylinder bore in an annular member 104a. Accordingly, the annular plunger 102a may be provided with external and internal hydraulic 25 packings 39b, 39c, to make tight joints with the walls of the cylinder 104a. The cylinder member 104a rests and gyrates (with the plunger 102a) on a wearing ring 103a mounted in the spider 100a. Fluid (oil) under pressure is admitted and 30 vented to and from the cylinder 104a through a duct 106 in the plunger 102a, to which there is a flexible connection 107 leading, through a swivel connector or universal 42a, to a pressure connection 44 of a system such as shown in Fig. I, or to 35 any suitable means of introducing and drawing off the pressure fluid. Oil admission to the cylinder 40 raises the head 15 relative to the crushing shell 10, and vice-versa.

45 As mentioned above, this Fig. V crusher is of the more ordinary and well-known type in which the upper end of the gyratory member 12 is fulcrumed in the spider hub 100a, and the eccentric 14a imparts the greatest motion to the lower end of said member 12. In other words, the cylinder 50 104a and plunger 102a constitute a (hydraulic) motor for raising and lowering the crushing head 13, and thereby also varying the effective length of the gyratory member 12.

55 In each of Figs. II-V, various parts and features are marked with the same reference character as corresponding parts and features in Fig. I or in other figures (sometimes with an added letter, "a", "b", etc.) as a means of dispensing with merely repetitive description.

60 Having thus described my invention, I claim:

1. A gyratory crusher comprising a frame with a crushing shell, a hub, and a subjacent bearing; a rotary eccentric in said hub with the axes of its external and internal surfaces intersecting in a neutral point of no-throw at said bearing; a substantially inflexible gyratory member engaged in said eccentric, and engaging said bearing at said neutral point, and having a crushing head in said shell above said eccentric and hub; and 65 annular sealing means coacting with said hub and said gyratory member to exclude dust from said eccentric while permitting gyration and vertical adjustment of the head.

70 2. A gyratory crusher comprising a frame with a crushing shell, a hub, and a subjacent bearing;

a rotary eccentric in said hub with the axes of its external and internal surfaces intersecting in a neutral point of no-throw at said bearing; a gyratory member including a shaft in said eccentric engaging said bearing at said neutral point, and 5 a crushing head in said shell, above said eccentric and hub, hollowed at its lower side to afford a skirt around the upper end of said hub; annular sealing means coacting with said hub and shaft to exclude dust or dirt from said eccentric while permitting gyration and vertical adjustment; and other annular sealing means similarly coacting with said hub and skirt.

3. A gyratory crusher comprising a crushing shell, a substantially inflexible gyratory member 15 including a crushing head gyrating in said shell, so as to vary their interval and crush material between them, a bearing for said member below said head; a rotary actuating eccentric around and engaging said inflexible gyratory member intermediate said head and bearing, with the axes of its external and internal surfaces intersecting in a neutral point of no-throw at said bearing, and supporting means for said bearing adjustable up and down to raise and lower the crushing head 20 in the shell.

4. A gyratory crusher comprising a crushing shell, a fixed supporting bearing, a gyratory member having a crushing head in said shell and engaging said supporting bearing at a substantially 25 fixed, invariable point of no-throw of the said gyratory member, an eccentric for imparting gyratory movement to said gyratory member, and means for varying the length of said gyratory member between its head and its said fixed, no-throw point of engagement with said bearing even during the operation of the crusher and the gyratory movement of the member.

5. A gyratory crusher comprising a crushing shell; a gyratory member having a crushing head in said shell and supported at its own lower end; means for adjusting the length of said gyratory member between its head and its support; and a rotary eccentric for gyrating said member engaged around it below its head.

6. A gyratory crusher comprising a crushing shell; a gyratory member including a crushing head in said shell having a shaft and a downward extension of said shaft supported below the same, said shaft and extension being relatively shiftable 50 in the axial direction; means for relatively shifting said shaft and extension as aforesaid, and a rotary eccentric around said shaft for gyrating said member and head.

7. A gyratory crusher comprising a crushing shell; a gyratory member including a crushing head in said shell having a shaft, and a downward extension of said shaft supported at its own lower end, said shaft and extension being telescopically interengaged and relatively shiftable in the axial direction; means for relatively shifting said shaft and extension as aforesaid; a rotary eccentric engaged around said gyratory member for gyrating it, with the axes of its external and internal surfaces intersecting in a neutral point 65 of no-throw at the lower end of said extension; and a no-throw bearing for said gyratory member at said neutral point.

8. A gyratory crusher comprising a crushing shell; a gyratory member including a crushing head in said shell having a shaft and a downward extension of said shaft supported below the same and held against turning, while free to gyrate, said shaft and extension being relatively shiftable 70 in the axial direction; means for relatively shift-

ing said shaft and extension as aforesaid, and a rotary eccentric engaged around said gyratory member for gyrating it, the axes of the external and internal surfaces of said eccentric intersecting in a neutral point of no-throw at the point of support of said extension.

9. A gyratory crusher comprising a crushing shell, a telescopically expansible and contractible gyratory member including a crushing head gyrating in said shell, means for imparting gyratory movement to said gyratory member, and means including a hydraulic motor in said member for telescopically expanding and contracting the same, and thus varying its effective length.

10. A gyratory crusher comprising a crushing shell, a gyratory member including a crushing head gyrating in said shell, a hydraulic support for said member including a gyrating cylinder and plunger telescoped one within the other, and means for introducing and venting fluid to and from said cylinder through said plunger.

11. A gyratory crusher comprising a crushing shell, a gyratory member including a crushing head in the shell and a hollow shaft, a plunger in the hollow of said shaft, supporting means for the lower end of said plunger, means for gyrating said gyratory member, and means for introducing and venting fluid to and from the hollow of said shaft.

12. A gyratory crusher comprising a crushing shell, a gyratory member including a crushing head in the shell and a hollow shaft, a plunger in the hollow of said shaft, supporting means for the lower end of said plunger, means for gyrating said gyratory member about a neutral point of no-throw, and means for introducing and venting fluid to and from the hollow of said shaft through the neutral point of said member.

13. A gyratory crusher comprising a crushing shell, a gyratory member including a crushing head in the shell and a hollow shaft, a plunger in the hollow of said shaft, a bearing support at the lower end of said plunger, said plunger and said support being anti-rotatively interengaged, means for gyrating said gyratory member about a neutral point of no-throw at said bearing support, and a flexible connection to the neutral point of said plunger for introducing and venting fluid to and from the hollow of said shaft.

14. A gyratory crusher comprising a crushing shell, a substantially inflexible gyratory member including a crushing head gyrating in said shell, so as to vary their interval and crush material between them, and having a neutral point of no-throw at the lower end of the gyratory member, a no-throw bearing and spring cushion means for yieldingly supporting the lower end of said gyratory member, and a rotary actuating eccentric around said member intermediate said head and bearing.

15. A gyratory crusher comprising a crushing shell, a substantially inflexible gyratory member including a crushing head gyrating in said shell, so as to vary their interval and crush material between them, and having a neutral point of no-throw at the lower end of the gyratory member, a no-throw bearing and spring cushion means for yieldingly supporting the lower end of said gyratory member, means for supporting said spring cushion means and adjusting the same up and down to raise and lower the crushing head in the shell, and a rotary actuating eccentric around said member intermediate said head and bearing.

16. The combination with a gyratory crusher comprising a crushing shell and a gyratory mem-

ber including a crushing head gyrating in said shell, so as to vary their interval and crush material between them, of a hydraulic pressure system including means for sustaining the normal working pressure between said head and shell; pressure relief means for automatically venting liquid out of said pressure system under excessive working pressure due to hard material between said head and the crushing shell, thus temporarily allowing said head to yield and recede downward; and means including a pump for automatically delivering liquid under pressure into said system, when the excessive working pressure is over, until said crushing head is restored to normal working position.

17. The combination with a gyratory crusher comprising a crushing shell and a gyratory member including a crushing head gyrating in said shell, so as to vary their interval and crush material between them, of hydraulic means for sustaining the working pressure between said head and shell, a pump for delivering liquid to said means under normal working pressure, and automatic relief means for by-passing and returning the pumped liquid from said means to the intake of said pump and thus allowing the gyratory head to yield and recede downward under excessive working pressure due to hard material between said head and the crushing shell.

18. The combination with a gyratory crusher comprising a crushing shell and a gyratory member including a crushing head gyrating in said shell, so as to vary their interval and crush material between them, of hydraulic means for sustaining the working pressure between said head and shell, a pump for delivering liquid to said means under normal working pressure, a liquid supply system including a receiver connected to the intake of said pump, and automatic relief means for by-passing and returning the pumped liquid from the delivery side of said pump back to said receiver and thus allowing the gyratory head to yield and recede downward under excessive working pressure due to hard material between said head and the crushing shell.

19. The combination with a gyratory crusher comprising a crushing shell and a gyratory member including a crushing head gyrating in said shell, so as to vary their interval and crush material between them, of hydraulic means for sustaining the working pressure between said head and shell, a pump for delivering liquid to said means under normal working pressure, a liquid supply system including a receiver connected to the intake of said pump, automatic relief means for by-passing and returning the pumped liquid from the delivery side of said pump back to said receiver, and thus allowing the gyratory head to yield and recede downward under excessive working pressure due to hard material between said head and the crushing shell, and manually controlled means for returning liquid from said hydraulic means back to said supply system.

20. The combination with a gyratory crusher comprising a crushing shell and a gyratory member including a crushing head gyrating in said shell, so as to vary their interval and crush material between them, of hydraulic means for sustaining the working pressure between said head and shell, a pump for delivering liquid to said means under normal working pressure, a liquid supply system including a closed receiver connected to the intake of said pump, an open receiver with a manually controlled connection for delivering into said closed receiver, automatic

relief means for by-passing and returning liquid from said hydraulic means to said closed receiver, and manually controlled means for returning liquid from said hydraulic means to said open receiver.

21. The combination with a gyratory crusher comprising a crushing shell and a gyratory member with a crushing head gyrating in said shell, of a hydraulic support for said member including a gyrating cylinder and plunger telescoped one

within the other, a system including a pump for delivering liquid to said cylinder under normal working pressure, and automatic relief means for venting the pumped liquid from said system and thus allowing the gyratory head to yield and recede downward under excessive working pressure due to hard material between said head and the crushing shell.
